REEVES PULLEY COMPANY, OF COLUMBUS, INDIANA, A CORPORATION OF INDIANA

VENEER-CUTTER-SPEED CONTROL

Application filed November 3, 1926. Serial No. 145,929.

Our invention relates to means for automatically controlling, in a veneer cutting machine, the speed at which the log from which the veneer is cut is rotated and particularly to means for maintaining the peripheral speed of the log constant as the cut is made deeper into the log.

It is one of the objects of our invention to provide a simple automatic mechanism operated by the feeding of the cutting knife to increase peripheral speed of the log as the peripheral surface decreases due to the cutting of the veneer therefrom.

For disclosing our invention we have illustrated one embodiment thereof in the accompanying drawings in which

Fig. 1 is a side elevation of an apparatus embodying our invention;

Fig. 2 is a plan view thereof.

In the structure illustrated the veneer cutting machine is of the usual commercial type including a bed or frame 1 in which is mounted a chuck mechanism 2 adapted to receive and rotate the log 3. This chuck mechanism is provided with one or more large driven gears 4 driven from a counter-shaft 5 provided with pinions 6 adapted to mesh with the gears 4.

The cutter knives 7 are mounted on a knife carriage 8 having side members 9 which operate in suitable guideways 10 in the bed or frame. This carriage is fed forward by a plurality of feed screws (only one of which is shown) 11 driven by a suitable gearing 12 from a driven pulley 13. The speed at which the carriage is fed forward is constant in order to maintain constant the thickness of the veneer cut from the log.

In this type of machine it is desirable that the peripheral speed of the log should remain the same and as the log is reduced in diameter by the cutting of the veneer this peripheral speed must be maintained constant by varying the speed at which the log is rotated. To this end we interpose between the

operating power and the log rotating mechanism a speed varying transmission which is preferably of the "Reeves" type in which there are two pairs of cone pulleys 14 and 15 connected by a V belt 16. The pulleys of each pair are splined on rotatable shafts 17 and 18 and are moved toward and away from each other on the shafts by means of suitable levers 19 and 20 fulcrumed respectively at 21 and 22. The pulleys are so connected to the levers 19 and 20 that as the levers are manipulated the pulleys of one pair will be moved toward one another while at the same time the pulleys of the opposite pair will be moved away from one another. In the present construction the ends of the levers 19 and 20 are connected by links 23 to a rocking arm 24 mounted on a shaft 25 so that as the shaft is rotated in one direction or the other the free ends of the levers will be moved toward or away from one another to thereby vary the distance between the pulleys of each pair. In the present instance the shaft 5 of the veneer cutting machine is driven by a belt and pulley connection 26 from the shaft 17 of the variable speed transmission and power is applied to the shaft 18 of this transmission.

The levers 19 and 20 are operated to cause the variable speed transmission to drive the cutting machine at different speeds, from the knife-feeding carriage. For accomplishing this result we provide a V shaped frame the two legs 27 of which are bolted or otherwise secured at their lower ends to the frame 1 of the veneer machine. At the apex of this frame there is provided a stub shaft 28 on which is mounted a rocking arm 29. The lower end of this arm is connected by a link 30 with an arm 31 bolted to the side member 9 of the knife carriage. The upper end of this arm is connected by a link rod 32 with one arm 33 of a bell crank lever, the opposite arm 34 of which is connected by a link rod 35 with an arm 36 secured on the shaft 25. In the present construction the transmission 90

is adapted to be supported from the ceiling of the compartment in which the veneer cutting machine is located and the bell crank lever is therefore supported from the ceiling by a suitable hanger bracket 37.

5 The operation of the apparatus is obvious. As the carriage 8 feeds inwardly during the cutting of the veneer the lower end of the arm 29 will move with the carriage thereby 10 rocking the upper end of the arm in an opposite direction, which motion is transmitted through the link rods 32 and 35 and the bell crank lever to the arm 36, which in turn rotates the shaft 25 to rotate the arm 24 moving the pair of cone discs 15 of the speed 15 transmission toward one another and the pair of cone discs 14 away from one another thereby gradually increasing the speed at which the shaft 5, and consequently the log 3, is rotated, this increase being in proportion to 20 the decrease in diameter of the log to thereby maintain the peripheral speed of the log constant.

We claim as our invention:

25 1. The combination with a veneer cutting machine having means for rotating the log and means for feeding the cutting knives toward said log, of a speed varying mechanism drivingly connected with the log rotating 30 means and comprising two pairs of friction cones, a connecting belt, two controlling levers acting upon said pairs of cones to variably position the same relatively to one another, means for simultaneously shifting controlling levers, and means operated by the 35 movement of the knives for operating said lever shifting means.

40 2. In an apparatus of the character described, the combination with a veneer cutting machine having means for rotating the log and means for feeding the cutting knives toward the log, of a speed varying mechanism drivingly connected with the log rotating 45 means and comprising two pairs of friction cones, a connecting belt, two controlling levers acting upon said pairs of cones to variably position the same relatively to one another and means for shifting said levers, and means connected with the knife feeding means for 50 operating said lever shifting means including a locking arm having one end connected to the knife feeding means and the other end connected to the lever shifting means.

55 3. In an apparatus of the character described, the combination with a veneer cutting machine having means for rotating the log and means for feeding the cutting knives toward the log, of a speed varying mechanism drivingly connected with the log rotating 60 means comprising two pairs of friction cones, a connecting belt, two controlling levers acting upon said pairs of cones to variably position the same relatively to one another, and means for shifting said levers, and a connection 65 between said lever shifting means and

knife feeding means including a supporting frame mounted on the cutting machine frame, a lever rockably mounted on said frame and having one end connected to the knife carriage and the other end connected to the lever shifting means.

In witness whereof we, HARRY C. CLAY and CHARLES L. IRWIN, have hereunto set our hands, at Columbus, Indiana, this 25th day of October, A. D. one thousand nine hundred 75 and twenty-six.

HARRY C. CLAY.
CHARLES L. IRWIN.
